METHOD OF SUPPLYING STEAM TO THE
RADIATORS OF STEAM HEATING SYS-
TEMS

Fred I. Raymond, River Forest, Ill.

Application June 22, 1931, Serial No. 546,126

20 Claims. (Cl. 237—12)

In the operation of steam heating systems as commonly provided the steam entering the feeder pipes flows first into those radiators nearest the boiler thereby producing unequal heating of the radiators. While this condition is not serious when the system is operated under continuous pressure, it is serious when the system is operated intermittently, as for example when the boiler is fired by a start and stop oil burner, because the radiators nearest the boiler will be heated for a longer time than the others each time the burner operates, and this causes a greater amount of heat to be delivered to the first rooms than to the last rooms.

One of my objects is to provide for the heating up of all of the radiators of a steam heating system substantially simultaneously, as distinguished from the heating of those radiators nearest the boiler before the others thereof become heated, thereby avoiding the objections above noted.

Generally stated my invention consists in improvements in the venting of the air from steam heating systems to the end that the air in the radiators of the systems will remain trapped therein until all of the air has been removed from the steam mains.

Referring to the accompanying drawings:

Figure 1 is a view in elevation of a one-pipe steam heating system illustrating one of the ways of practicing my improved method.

Figure 2 is a similar view of a modification of the system of Fig. 1 and illustrating another way of practicing my improved method.

Figure 3 is a similar view of another one-pipe steam heating system in which the steam is fed downward from an overhead steam main, and illustrating still another way of practicing my improved method.

Figure 4 is a similar view of a two-pipe steam heating system and illustrating still another way of practicing my improved method.

Figure 5 is a similar view of a modification of the system shown in Fig. 4 and illustrating still another way of practicing my improved method.

Figure 6 is a similar view of a large two-pipe steam heating system wherein the steam is fed to down-feed risers from an overhead steam main and illustrating still another way of practicing my improved method.

Figure 7 is a similar view of another two-pipe steam heating system and illustrating still another way of practicing my improved method.

Figure 12 is a view in elevation of a steam heating system of the dry return type and illustrating still another way of practicing my improved method; and

Figure 13, a view in sectional elevation of a float-equipped vent valve forming a part of the installation of Fig. 12.

Referring to the system shown in Fig. 1, a boiler 9 supplies steam through a pipe 10 to a steam main 11, the steam being supplied from the steam main 11 to the radiators, represented at 13, through riser pipes 14, the water of condensation from the radiators 13 flowing by gravity back to the boiler 9 through the risers 14, the steam mains 11 and return lines 15 and 16 connected with the bottom of the boiler 9, the steam main sloping at its opposite ends toward the return lines 15 and 16 as shown.

Each radiator 13 is equipped with a thermostatic vent valve represented at 17 which may be of a type commonly used for the purpose of permitting air to escape from the radiator but preventing the escape of steam therefrom, except that the vent valves 17 in this case are each provided with a weight or spring (not shown) to hold the air-escape valve against its seat until a predetermined pressure is attained in the radiator equipped therewith.

At the ends of the steam main 11 similar vent valves represented at 18 are provided, these valves being designed to open to the passage of air at a pressure considerably below that at which the vent valves 17 open to the flow of air therethrough, the air escapement valves proper of the valves 18 preferably presenting a large area.

In operation this system functions as follows: Assuming the steam main 11 to be cold and full of air, generation of steam in the boiler 9 causes steam to flow therefrom through the steam main 11, resulting in an increase of the pressure in this main thereby forcing the air therein out through the vent valves 18, the vent valves 17 remaining closed inasmuch as the latter open at a higher pressure than the vent valves 18, thus venting

the steam main before the radiators are vented. Since the valves 18 are of relatively large capacity, it will not be possible to build up an appreciable pressure in the system until they close. 5 Therefore, the steam supplied to the main 11 will flow out to the ends of the latter in preference to flowing into the radiators from which no air can escape at the lower pressure. When steam reaches the ends of the steam main 11 the vent 10 valves 18 automatically close by thermostatic action of the steam thereon; and as soon as both of the valves 18 close, further generation of steam in the boiler will increase the pressure in the system to a point where the valves 17 open and permit 15 of the discharge from the radiators 13 of the air trapped therein, thus venting the radiators after the steam main has been vented. The steam is thus simultaneously, and at substantially the same pressure, supplied to all of the radiators. 20 By providing the valves 17 of small size, it will not be possible for one of these valves to vent air in sufficient volume to prevent further raising of the pressure in the system.

Thus there will be a material increase in pressure in the system when the valves 18 close and this material increase in pressure will cause all of the valves 17 to open, even though there may be a slight difference in their opening pressures and effect simultaneous supply of steam to all of the 30 radiators.

Referring to the system shown in Fig. 2, a boiler represented at 19 supplies steam through a pipe 20 to a steam main 21, this main supplying steam, through risers 23, to radiators represented 35 at 24 equipped with thermostatic vent valves 25 of standard design.

Condensation from the radiators 24 is returned, by gravity, to the boiler 19 through the risers 23, the steam main 21 and return air lines 26 and 27, 40 the latter opening into the bottom of the boiler 19.

This arrangement also comprises a vacuum pump 28 shown as driven by an electric motor 29, the inlet of this pump being connected with a pipe 30 which opens into pipes 31 and 32 in 45 communication with the ends of the steam main 21 and the outlet thereof provided with an outwardly opening check valve 34, the pipes 31 and 32 having interposed therein thermostatic traps 33, as for example of standard design.

50 In operation, the entire system will be held under partial vacuum by the vacuum pump 28 so long as the thermostatic traps 33 are open. Therefore when the boiler 19 starts to generate steam, the steam will flow out to the ends of the 55 steam main 21 rather than into the branch risers 23 and radiators 24, thus venting the steam main before the radiators are vented. As soon as the steam reaches the thermostatic traps 33 the latter automatically close so that further generation 60 of steam in the boiler 19 produces a rise in pressure in the system above atmospheric pressure thereby causing steam to enter all of the risers 23 simultaneously as described in connection with the operation of the system shown in 65 Fig. 1, thus venting the radiators after the steam main has been vented, it being understood that the rise above referred to of the pressure in the system forces open the vent valves 25 to permit the air to vent from the radiators.

70 Referring to the system shown in Fig. 3, a boiler represented at 35 connects, by an upwardly extending pipe 36, with an overhead main 37 from which steam is supplied to down-feed risers 38 constituting parts of the main 37 and opening 75 into the pipe 37 at different points along the

latter as shown. Each riser 38 is shown as connected by pipes 39 with a vertical series of radiators 40 each of which is provided with a thermostatic vent valve 41 of standard design. The system shown is provided for the supplying of 5 steam to radiators a plurality of which are located on each floor of a building, as for example, and as shown in the drawings, four floors.

The condensation from the radiators 40 flows, by gravity, from the radiators to the risers 38 10 and thence to float traps 42 of standard design which operate to permit the passage of water to a return line 43 connected with these traps by pipes 44, but which close to the passage of air or steam therethrough. 15

The system also comprises a vacuum pump represented at 45 the inlet of which communicates with a pipe 46 which extends upwardly into a receiver 47 in communication at its top with the pipe 43, by a pipe 48, the outlet of the pump 45 20 represented at 49 being provided with an outwardly opening check valve 50 like the valve 34 of Fig. 2. The bottom of the tank 47 communicates by a pipe 51 with a boiler-feed pump 52 the outlet of which communicates by a pipe 53 with 25 the bottom of the boiler 35.

The system also comprises thermostatic traps represented at 38^a communicating with the lower portions of the down-feed risers 38 by pipes 38^b 30 and with the return line 43 by pipes 43^a, the traps 38^a permitting of the passage of air from the risers 38 to the return line 43 and the escape therefrom through the check valve 50, by the operation of the pump 45, but closing to the passage of steam. 35

The operation of this system is similar to that of the system shown in Fig. 2, the only difference being in the addition of the float traps 42 which permit the return line 43 to be used as the air line as well as the condensate return line. 40

So long as any of the thermostatic traps 38^a are cold indicating that steam has not yet filled the steam main 37 and risers 38, the system will be maintained under a partial vacuum by the vacuum pump 45 and the air in the radiators 40 will 45 remain trapped therein. When all the steam traps 38^a become closed by the presence of steam therein, the vacuum pump 45 no longer exerts suction on the risers 38, the float traps 42 being closed as they open only upon the collection of condensate therein, and thus in the continued operation of the boiler the pressure in the pipes 36, 37 and 38 rises above atmospheric thus forcing the air out of the radiators 40 through the vents 41 and simultaneously supplying steam to all of the 55 radiators.

Referring to the system shown in Fig. 4, which constitutes an embodiment of my invention in a so-called two-pipe steam heating system of common design, the boiler 54 connects by a pipe 55 with a steam main 56 from which steam is supplied through risers 57 to radiators represented at 58. The radiators 58 are provided with thermostatic steam traps 59 which open into a return line 60 discharging through a pipe 61 having a short water leg section 62, into the bottom of a separator 63 equipped with an outwardly opening check valve represented at 64. The separator 63 is connected by a pipe 65 with an alternator 66 as for example of standard design and to which the condensate in the separator 63 flows through the pipe 65. The upper end of the alternator 66 connects by a pipe 67 with the steam main 56 and the condensate-outlet of the alternator 66 connects by a pipe 68 with the bottom of the boiler 70 75 80 85 90 95 100

54. This alternator is provided in accordance with common practice for the purpose of returning condensate to the boiler against pressure.

The upper portion of the separator 63 connects, 5 by pipes 69, with thermostatic traps 70 located at the ends of the steam main 56, the traps 70 being open to the flow of air and water therethrough and closing to the passage of steam.

The operation of this system is as follows: The 10 generation of steam in the boiler 54 causes steam to flow through the pipe 55 and into the steam main 56. As the steam progresses into the main 56 it displaces the air therein, the air following the path of least resistance to the atmosphere 15 which is through the steam traps 70, return line 69, separator 63, and check valve 64 to the atmosphere, rather than through the risers 51, radiators 58, traps 59, return line 60, pipe 61, with its water leg 62, separator 63, and check valve 20 64, thus venting the steam main before the radiators are vented. Even without the water leg 62 there would be a greater flow of air from the return line 69 than from the return line 60, but the water leg 62 in the return line 69 produces a 25 definite and positive seal which prevents the flow of any air therethrough until the pressure in the return line 60 rises sufficiently above atmospheric pressure to blow the water out of the water leg 62.

30 Steam will therefore flow along the steam main 56 without branching off into the risers 59, until the steam main 56 is completely filled with steam which causes the thermostatic traps 70 to close. The closing of the thermostatic traps 70, due to 35 the presence of steam therein, prevents the further escape of steam therethrough and the continued generation of steam in the boiler 54 creates an increase in pressure in the system, this pressure finally becoming sufficient to blow the 40 water from the water leg 62 and permit the escape of air from the radiators 58 through the return line 60, thus venting the radiators after the steam main has been vented. Inasmuch as the steam main 56 is filled with steam, the steam, in the 45 venting of the radiators as stated, will start to flow into all the radiators substantially simultaneously.

In this arrangement it is desirable, though not necessary, that the piping between the steam traps 59 and the separator be equipped with an inwardly opening check valve as indicated at 61^a, which permits breaking of the vacuum in the return line 60 thereby preventing leakage of air into the steam main which, as will be manifest, 55 it is desired be avoided.

Referring to the system shown in Fig. 5, which is of the so-called two-pipe steam heating type of system equipped with a combination vacuum and condensation return pump, the boiler, represented 60 at 71, supplies steam through a pipe 72 to a steam main 73 connected, by pipes 74, with radiators 75 provided with steam traps 76 opening into a return line 77 communicating with a pipe 78 having a lower, water leg, section 79 opening into the bottom of a receiver 80.

Steam traps 81 are provided at the ends of the main 73 these traps being connected with a return line 82 connected with a pipe 83 which opens 70 into the top of the receiver 80.

The receiver 80 forms an element of a combination vacuum and condensation pump structure represented generally at 84 and comprising a vacuum pump 85 the inlet of which communicates 75 with a pipe 86 extending upwardly into the re-

ceiver 80 and the outlet of which connects with a pipe 87 having an outwardly opening check valve 88. The structure 84 also comprises a boiler feed pump 89 connected at its inlet, through a pipe 90, with the bottom of the receiver 80 and, 5 by a pipe 91, with the bottom of the boiler 71.

The operation of this system is as follows: In starting this system the vacuum pump 85 will withdraw air from the mains 73 through the steam traps 81, return line 82, pipe 83, receiver 80, pipe 10 86, exhausting the air through the check valve 88, the air in the radiators 75 remaining therein due to the greater resistance to flow through the risers 74, radiators 75, return line 77, pipe 78, and its water leg 79, the steam main thus being vented 15 before the radiators are vented. Steam will therefore be drawn out to the ends of the steam main 73 before the steam branches off into the risers 74. Upon the closing of the steam traps 81 by the presence of steam therein, and thus 20 throughout the extent of the steam main 73, the suction created by the vacuum pump 85 can no longer be relieved by flow through the traps 81, pipes 82 and 83 and separator 63, whereupon the vacuum created by the pump increases in the 25 receiver 80 until it is sufficient to overcome the resistance of the water in the water leg 79 whereupon the water will be blown from this leg and air will then be drawn from all of the radiators 75 substantially simultaneously through the steam 30 traps 76, return lines 77, pipe 78, separator 80, pipe 86, pump 85, and check valve 88 to the atmosphere, thus venting the radiators after the steam main has been vented and as at this time the steam mains 73 are filled with steam, the entry of steam into all of the radiators 75 will occur 35 substantially simultaneously.

Referring to the system shown in Fig. 6 which is of the so-called two-pipe steam heating type of system widely used in tall buildings, and comprising down feed risers, the elements of this system are substantially the same as those shown in Fig. 5 with the exception that the down feed risers constitute portions of the steam main. In this system the boiler is represented at 92 and connects with a pipe 93 opening into an overhead steam main 94 from which down feed risers 95 lead. Each riser 95 is shown as connected by pipes 96 with a vertical series of radiators 97 each of which is provided with a steam trap 98 which opens into a return line 99 connected with pipes 100 opening into a pipe 101 having a lower water leg 102 opening into the bottom of a receiver 103.

At the lower ends of the risers 95 are relatively large thermostatic traps 104 connected with a 55 return line 105 opening into a pipe 106 which communicates with the top of the receiver 103. A combination vacuum and condensation pump is represented at 107, the vacuum pump 108 of which connects at its inlet with a pipe 109 opening into the upper end of the receiver 103 and its outlet connecting with a pipe 110 having an upwardly opening check valve 111. The boiler feed pump element of this apparatus is represented at 112, this pump connecting at its inlet with a pipe 113 60 which opens into the bottom of the receiver 103 and at its outlet with a pipe 114 which opens into the bottom of the boiler 92.

As the system now being described functions in the same manner as the system shown in Fig. 70 5 repetition of the description of the operation is unnecessary.

It will be understood from the foregoing that in the systems shown in Figs. 1 to 6, inclusive, the filling of the steam mains, before flow of steam 75

into the radiators, is accomplished by providing greater resistance to the flow of air through the radiators than from the steam mains thereby insuring the filling of the steam mains before 5 starting to fill the radiators with steam. In other words, air flows from the steam mains at a lower pressure than it does from the radiators.

The method may also be practiced by a system 10 wherein the air is vented from the radiators at the same pressure as that it which it is vented from the steam mains, Fig. 7 showing such a system and employing as an element thereof a special valve, shown in detail in Fig. 8, which operates to cause the air to be forced from the steam main 15 before starting the flow of the air from the radiators.

The system shown in Fig. 7 comprises a boiler 115 connected with a pipe 116 opening into a steam main 117 connected, by risers 118, with 20 radiators 119 equipped with steam traps 120 which communicate through branch pipes 121 with a dry return line 122, provided with an inwardly opening check valve 122^a for the purpose above explained in connection with check valve 6^{1a} of Fig. 4. The steam main 117 and the dry return line 122 connect with pipes 123 and 124, respectively, which open at their lower ends into a wet return line 125 for draining by gravity into the latter condensation in the lines 117 and 122. The 30 wet return line 125 drains into an alternator 126 of common design which returns the condensate to the boiler through pipe 127 even though the pressure in the boiler may be greater than the pressure in the return line.

35 The system now being described also comprises a special form of valve represented generally at 128 the details of which are shown in Fig. 8. This valve comprises a casing 129 divided by partitions 130 and 131 into an upper compartment 132, a lower compartment 133, and an intermediate compartment 134. The compartment 132 communicates with the steam line 117 beyond the connection of the latter with the drain pipe 123 and the compartment 133 communicates with the dry return line 122 beyond its connection with the drain pipe 124; and the compartment 134 connects by a pipe 135 with an outwardly opening check valve 136.

The partitions 130 and 131 contain ports 137 50 and 138 extending therethrough and with which oppositely facing conical valves 139 and 140 co-operate. The valves 139 and 140 are provided on the stem 141 of a thermostatic bellows 142 mounted on the top of the casing 129 this bellows being 55 shown as of the common expansible corrugated chamber type containing liquid that boils at a temperature slightly under that of steam. The valve member 140 is shown as adjustable along the stem 141 relative to the valve 139, these valves 60 being so spaced that at no time are both valves seated.

The operation of this system is as follows: Assuming the system to be cold, the starting up of the boiler 115 causes steam to flow through pipe 116 into the steam main 117. In the cold condition of the apparatus the valve 140 will be seated to close the port 138 and the valve 139 unseated to open the port 137 whereby the steam main 117 will be in communication through the compartments 132 and 134 with the check valve 136. Thus the air in the steam line 117 will be driven therefrom, the radiators 119 being closed to the escape of air therefrom by the closed condition of the valve 140, thus venting the steam main 70 before the radiators are vented. When the steam

main 117 becomes filled with steam and the steam contacts with the thermostatic bellows 142, this bellows expands forcing the valve 139 to seated position and closing the port 137 and forcing the valve 140 to open position thereby closing the steam line to the escape of steam therethrough to valve device 128 and opening the dry return line 122 and consequently the radiators for the escape therefrom of the air therein out through the check valve 136, thus venting the radiators after 10 the steam main has been vented. Inasmuch as the steam line 117 has been filled with steam before the air may vent from any of the radiators, the actuation of the valve 128 to close the steam main 117 to the escape of steam therefrom and 15 open the return line 122 to the atmosphere, permits the air in the radiators to escape substantially simultaneously from all of the radiators and consequently the steam will flow into all of the radiators substantially simultaneously. 20

Referring to the system shown in Figs. 9, 10 and 11, the boiler represented at 143 connects by a pipe 144 with a steam main 145 from which the steam is supplied, through risers 146, to radiators represented at 147. The radiators 147 are 25 provided with thermostatic steam traps 148 which open into a dry return line pipe 149 connected with a pipe 150, the latter opening into a pipe 151 leading into a return trap 152 the outlet of which connects by a pipe 153 with the bottom 30 of the boiler 143, the trap 152 also being connected with the steam line 144 by a pipe 154.

At the ends of the steam main 145 are vent valves 155 comprising chambers 156 communicating through their side walls with the ends of the 35 steam main 145 and through their bottom walls with the upper ends of pipes 157 which open into the return line pipe 150, the water and air or steam discharging from the steam line 145 into the chambers 156. The chambers 156 are in effect 40 separating chambers in which the water settles to the bottoms thereof and flows out through the pipes 157 to the wet return line pipe 150, air or steam entering the chambers 156 rising to the top of these chambers. 45

The chambers 156 contain outlet ports 158 shown as opening into supplemental chambers 159 having vents 160 the ports 158 being normally closed by disks 161 located in the supplemental chambers and upwardly displaceable. 50

The chambers 156 also contain thermostatic valve mechanisms controlling the outputs 158 and comprising expansive elements 162, shown as bellows, supported on spiders 163 in the chambers 156 and having valves 164 which are normally 55 open but which close when the elements 162 become heated by contact therewith of steam.

The return line 149 is connected with a vent valve 165 (Fig. 10) comprising a casing 166 open to the line 149 and containing an outlet port 167 in its top wall which opens into a chamber 168 having side vents 169 and housing a disk 170 which is much heavier than the disks 161 and normally closes the outlet port 167, but which is vertically displaceable to uncover this port, the line 149 also having an inwardly opening check valve 171 functioning for the purpose above explained as to valve 6^{1a}. 60

The operation of the system is as follows:

The generation of steam in the boiler 143 causes 70 steam to flow through the pipe 144 and into the steam main 145. As the steam progresses into the main 145 it displaces the air therein which flows into the vent valves 155 lifts the valve disks 161 and discharges to the atmosphere, thus venting 75

the steam main before the radiators are vented. While the vent valve 165, which is open to the outlets of the radiators, is also open to the steam main 145, this valve remains closed during the venting of the air from the steam main because the disk 170 is heavier than the disks 161. Upon the passage of steam into both valves 155 and the heating of the expansion elements 162 therein the valves 164 close the vents 160 and upon rise of pressure of steam in the system valve 165 automatically opens to vent the radiators 147. Thus the steam line will become completely filled with steam before any steam can enter any of the radiators and when the steam line thus becomes filled with steam, steam will start to enter all of the risers 146 simultaneously thus heating all of the radiators simultaneously.

It will be understood that it is not necessary that both of the valves 155 vent at the same pressure so long as they both vent at a pressure substantially below that at which the vent 165 opens. Should valves 155 vent at different pressures the one venting at lower pressure will close, and the steam will fill this end of the steam line first and therefore fill the other end before the valve 165 opens to permit steam to flow into the radiators.

Referring to the system shown in Figs. 12 and 13, the boiler 172 connects by a pipe 173 with a steam main 174 communicating with risers 175 opening into the radiators 176 the outlets of which open into pipes 177 communicating with a return line 178. A return trap 179 connects at its upper end with pipes 181 and 180 which open, respectively, into the steam main 174 and the return line 178, and opens at its bottom into a pipe discharging into the bottom of the boiler 172.

At the ends of the steam main 174 and the return line 178 are float-equipped thermostatic vent valves 182 comprising casings 183 containing main and supplemental chambers 184 and 185, respectively, communicating through ports 186 in the top walls of chambers 185, the pipe 174 opening into the main chambers 184 and the pipe 178 opening into the supplemental chambers 185. The water of condensation flowing in the pipe 174 returns to the boiler 172 through the casings 183 and to control this flow the valve structures 182 are provided with valves 187 operated by floats 188 in the chambers 184 and maintaining the chambers 185 closed to chambers 184 except when the water of condensation accumulates in the chambers 184 to such a height as to force the floats 188 to valve-raising position.

The valves 182 also comprise thermostatic means for venting the line 174 of air shown as of the same construction as the valves 155 of the preceding figures, the outlet-port-controlling disks of which are represented at 189 and the expansion-element-controlled valves at 190.

The line 178 is also provided with a vent valve 191 of the same construction as the vent valve 165 and operative to open position by the exertion against its outlet-port-controlling disk of greater pressure than required to open the disks 189 of valves 182 as in the case of valve 165.

The operation of the system now being described is the same as that shown in Fig. 9 except that the water in the wet return line of Fig. 9 operates to prevent the flow of air from the steam main into the return line, whereas in the system of Fig. 12 the float valves act to prevent the flow of air from the steam main into the return line.

The line 178 is also shown as provided with an

inwardly opening check valve 192 which performs the same function as that performed by the check valve 61^a of Fig. 4.

It will be noted that as to those of the systems above described which involve the venting of the steam mains at a lower pressure than that at which the radiators are vented, one of the features is the provision of a single air-vent valve for all of the radiators whereby simultaneous filling thereof with steam is assured, whereas a plurality of vents may be provided for the steam main and these vents function at different pressures provided they open at lower pressures than the vent for the radiators.

While I have illustrated and described certain constructions of apparatus by which my improved method may be practiced, I do not wish to be understood as intending to limit it thereto as the method may be practiced by the use of other constructions of apparatuses without departing from the spirit of my invention.

What I claim as new, and desire to secure by Letters Patent, is:

1. The method of supplying steam substantially simultaneously to a plurality of radiators connected with a steam main, which consists in first venting the air from the steam main while maintaining the air in the radiators against escape therefrom, and thereafter venting air from the radiators.

2. The method of supplying steam substantially simultaneously to a plurality of radiators connected with a steam main, which consists in forcing the air from the steam main by the pressure of steam supplied thereto while maintaining the air in the radiators against escape therefrom, and thereafter forcing the air from the radiators by the pressure of the steam.

3. The method of supplying steam substantially simultaneously to a plurality of radiators connected with a steam main, which consists in venting the air from the steam main and separately therefrom venting the air from the radiators and in maintaining the air in the radiators against escape therefrom until the steam main has become filled with steam.

4. The method of supplying steam substantially simultaneously to a plurality of radiators connected with a steam main, which consists in venting the air from the steam main and separately therefrom venting the air from the radiators and in maintaining the air in the radiators against escape therefrom until the steam main has become filled with steam at a predetermined pressure.

5. The method of supplying steam substantially simultaneously to a plurality of radiators connected at one end to a steam main and at the other end to a system of air collecting piping which consists in first venting the air from the steam main while maintaining the air in the system of air collecting piping against escape therefrom and thereafter venting the air from the system of air collecting piping.

6. The method of supplying steam substantially simultaneously to a plurality of radiators connected at one end to a steam main and at the other end to a system of air collecting piping which consists in first venting the air from the steam main while maintaining the air in the system of air collecting piping against escape therefrom and thereafter venting the air from the system of air collecting piping at a single point.

7. The method of supplying steam substantially simultaneously to a plurality of radiators con-

- nected at one end to a steam main and at the other end to a system of air collecting piping which consists in forcing the air from the steam main to the atmosphere by the pressure of steam supplied thereto while maintaining the air in the system of air collecting piping against escape therefrom and thereafter forcing the air from the system of air collecting piping to the atmosphere by the pressure of the steam.
8. The method of supplying steam substantially simultaneously to a plurality of radiators connected at one end to a steam main and at the other end to a system of air collecting piping which consists in forcing the air from the steam main to the atmosphere by the pressure of steam supplied thereto while maintaining the air in the system of air collecting piping against escape therefrom and thereafter forcing the air from the system of air collecting piping at a single point to the atmosphere by the pressure of the steam.
9. The method of supplying steam substantially simultaneously to a plurality of radiators connected at one end to a steam main and at the other end to a system of air collecting piping which consists in venting the air from the steam main and separately therefrom venting the air from the system of air collecting piping, and in maintaining the air in the system of air collecting piping against escape therefrom until the steam main has become filled with steam.
10. The method of supplying steam substantially simultaneously to a plurality of radiators connected at one end to a steam main and at the other end to a system of air collecting piping which consists in venting the air from the steam main and separately therefrom venting the air from the system of air collecting piping at a single point and in maintaining the air in the system of air collecting piping against escape therefrom until the steam main has become filled with steam.
11. The method of supplying steam substantially simultaneously to a plurality of radiators connected at one end to a steam main and at the other end to a system of air collecting piping which consists in venting the air from the steam main and separately therefrom venting the air from the system of air collecting piping, and in maintaining the air in the system of air collecting piping against escape therefrom until the steam main has become filled with steam at a predetermined pressure.
12. The method of supplying steam substantially simultaneously to a plurality of radiators connected at one end to a steam main and at the other end to a system of air collecting piping which consists in venting the air from the steam main and separately therefrom venting the air from the system of air collecting piping at a single point and in maintaining the air in the system of air collecting piping against escape therefrom until the steam main has become filled with steam at a predetermined pressure.
13. The method of supplying steam substantially simultaneously to a plurality of radiators connected to a steam main which comprises vent-

ing the air from the steam main, separately therefrom venting the air from the radiators and arresting the venting of air from the radiators until the pressure in the radiators exceeds the pressure at which air vents freely from the steam main. 5

14. The method of supplying steam substantially simultaneously to a plurality of radiators connected at one end to a steam main and at the other end to a system of air collecting piping which comprises venting the air from the steam main, separately therefrom venting air from the system of air collecting piping, and arresting the venting of air from the system of air collecting piping until the pressure in the system of air collecting piping exceeds the pressure at which air vents freely from the steam main. 10

15. The method of supplying steam substantially simultaneously to a plurality of radiators connected with a steam main which comprises venting the air from the steam main to the atmosphere, venting the air from the radiators to the atmosphere, and arresting the venting of air from the radiators until the pressure in the radiators exceeds the pressure at which air vents freely from the steam main. 20

16. The method of supplying steam substantially simultaneously to a plurality of radiators connected with a steam main which comprises venting the air from the steam main into a sub-atmospheric space and subsequently venting the air from the radiators to the atmosphere. 25

17. The method of supplying steam substantially simultaneously to a plurality of radiators connected with a steam main which comprises venting the air from the steam main into a sub-atmospheric space, venting the air from the radiators into a sub-atmospheric space, and maintaining the space into which air vents from the steam main at a lower absolute pressure than the space into which the air vents from the radiators. 35

18. The method of supplying steam substantially simultaneously to a plurality of radiators connected with a steam main which comprises venting the air from the steam main, separately therefrom venting the air from the radiators, and in thermostatically sealing the air in the radiators until the end of the steam main has become heated by the presence of steam therein. 45

19. The method of supplying steam substantially simultaneously to a plurality of radiators connected at one end to a steam main and at the other end to a system of air collecting piping which comprises venting the air from the steam main, separately therefrom venting air from the system of air collecting piping, and thermostatically sealing the air in the system of air collecting piping until the end of the steam main has become heated by the presence of steam therein. 55

20. The method of supplying steam substantially simultaneously to a plurality of radiators connected to a steam main which comprises, independently venting air from the steam main and from the radiators in the order of venting the air from the steam main before starting the venting of the air from the radiators. 60
